NONCATALYTIC HALOGENATION OF CERTAIN ALKYLATED ACRYLONITRILES

George W. Hearne, El Cerrito, Donald S. La France, Richmond, and Theodore W. Evans, Oakland, Calif., assignors to Shell Development Company, San Francisco, Calif., a corporation of Delaware

No Drawing. Application June 28, 1946,
Serial No. 680,082

7 Claims. (Cl. 260—465.7)

1

This invention relates to a process for effecting the halogenation, via substitution, of unsaturated organic nitriles.

More particularly, the process is directed to substitutive halogenation in the allyl position of unsaturated organic nitriles containing at least four carbon atoms and having an olefinic bond between two carbon atoms at least one of which is adjacent to a carbon atom having a substitutable hydrogen atom attached thereto. The process is carried out in its more general aspects by submitting the above and hereinafter defined class of unsaturated organic nitriles to the action of a halogen at an elevated temperature which promotes substitutive reaction between the nitrile and the halogen but below a temperature at which substantial degradation of the unsaturated organic nitrile or the halogen-substituted unsaturated organic nitrile may occur.

The halogen-substituted unsaturated organic nitriles that are obtained in accordance with the process of the present invention contain the halogen atom in the allyl position relative to the olefinic bond, that is, attached to a non-olefinic carbon atom that is directly linked to an olefinically bonded carbon atom. They are of high value as intermediates for the production of numerous chemical compounds and materials derived therefrom, such as pharmaceutical compounds, special solvents, products serving useful purposes in the art of synthetic resins, and other materials. Because of the presence in the same molecule of the reactive carbonitrile group, an olefinic bond, and a reactive halogen atom attached to a carbon atom adjacent to an olefinic carbon atom, the halogen substituted unsaturated organic nitriles that are obtained by the practice of the present process are of particular value for the preparation of a wide variety of useful chemical compounds. The present invention provides a process whereby a variety of valuable organic compounds may be synthesized on a commercial scale at a cost commensurate with industrial requirements, and in good yield and quality.

The unsaturated organic nitriles which may be subjected successfully to substitutive halogenation in accordance with the process of the present invention are those unsaturated organic nitriles which contain at least four carbon atoms and at least one olefinic bond between a pair of carbon atoms at least one of which is directly linked to a carbon atom of aliphatic nature having a substitutable hydrogen atom attached thereto. The present invention thus includes within its scope

2

only those unsaturated organic nitriles which contain a substitutable hydrogen atom in the allyl position in respect to an olefinic bond. The unsaturated organic nitriles that may be halogen substituted in accordance with the process of the present invention may contain an olefinic bond either in a position conjugate to the polyvalent bond of the carbonitrile group or in a position non-conjugate thereto. The olefinic bond thus 5 may be either in the alpha-beta position in respect to the carbonitrile group or it may be elsewhere in the molecule. In either case, however, it is essential for the purposes of the present invention that the organic nitrile have a substitutable 10 hydrogen atom attached to at least one non-olefinic carbon atom adjacent to an olefinically bonded carbon atom.

Representative unsaturated organic nitriles containing at least four carbon atoms and having 15 an olefinic bond in a position conjugate to the polyvalent bond of the carbonitrile group are, for example, the secondary, straight chain nitriles such as crotononitrile, 2-pentenenitrile, 2-hexenenitrile, 2-heptenenitrile and homologous compounds and the like. Instead of such straight chain nitriles, there may be employed analogous branched chain nitriles having an olefinic bond in a position conjugate to the polyvalent bond of the carbonitrile group; for example, the unsaturated nitriles having a substitutable hydrogen atom in the allyl position in respect to the double bond, such as methacrylonitrile, alpha-ethylacrylonitrile, alpha-(iso-amyl)acrylonitrile, 2-methyl-2-butenenitrile, 2-ethyl-2-butenenitrile, 2,5-dimethyl-2-hexenenitrile, 2-ethyl-5-methyl-2-hexenenitrile and similar or homologous unsaturated nitriles and the like; as well as other branched chain unsaturated nitriles such as 5-methyl-2-hexenenitrile, 4-methyl-2-hexenenitrile, and the like. The foregoing named alpha-, beta-unsaturated nitriles and the unsaturated nitriles employed in the examples herein included will be seen to contain at least four carbon atoms and to be of the general formula

45

in which one R represents an alkyl group and the second R represents a member of the group consisting of the hydrogen atom and the alkyl groups, and further to contain an atom of hydrogen in the allyl position relative to the alpha-, beta-olefinic bond and to contain a total of not over nine carbon atoms. Unsaturated organic 55 nitriles that contain the olefinic bond in a posi-

tion non-conjugate to the polyvalent bond of the carbonitrile group and which may be halogen substituted advantageously in accordance with the present invention, are for example the straight chain or the branched chain unsaturated nitriles such as 3-butenenitrile (vinylacetonitrile), 3-pentenenitrile, 4-pentenenitrile, 2-methyl-3-pentenenitrile, 3-methyl-3-pentenenitrile, 2-isoamyl-4-methyl-3-pentenenitrile, similar alkyl substituted hexenes having the olefinic bond in a position non-conjugate to the polyvalent bond of carbonitrile group, and analogous substituted heptenes, octenes, etc. It is preferred to employ in the process of the present invention the unsaturated organic nitriles having an olefin bond in a position conjugate to the polyvalent bond of the carbonitrile group. The process of the present invention also includes within its scope the halogen-substitution of unsaturated cyclo-organic nitriles which contain an olefinic bond either conjugate or non-conjugate to the polyvalent bond of the carbonitrile group, such as, for example, 2-cyclohexene-1-carbonitrile, 3-cyclohexene-1-carbonitrile, 2-methyl-3-cyclohexene-1-carbonitrile and similar or homologous cyclo-organic nitriles containing a cyclo-olefinic structure. The substituted halogenation of either straight-chain, branched chain, or cyclic olefinic organic nitriles containing more than one olefinic bond also is contemplated as within the broader aspects of the present invention. Representative di-olefinic nitriles thus are 2,5-hexadienenitrile, 1,3-cyclohexadiene-1-carbonitrile, 4-methyl-3,5-hexadiene-nitrile, etc. It will be understood that the foregoing and other compounds falling within the general and/or more limited classes of unsaturated nitriles adaptable to the purposes of the present invention, may contain additional substituent groups that are stable under the conditions of reaction and that do not prevent the desired halogen substitution reaction from taking place. Thus, there may be employed, unsaturated olefinic nitriles containing for example, an aromatic nucleus such as a benzyl group, a phenyl group, and the like, a cycloparaffinic group such as the cyclohexyl group, etc., one or more halogen atoms either different from or the same as the halogen to be introduced into the molecule, and similar substituent groups.

The process of the present invention is of particular advantage in its application to the alpha, beta unsaturated organic nitriles which have an alkyl substituent group attached to the alpha carbon atom and a substitutable hydrogen atom on the non-olefinic carbon atom adjacent to the alpha carbon atom; i. e., to the halogenation via substitution of methacrylonitrile and its homologs. This class of compounds may be represented by the general structural formula

wherein each R represents either hydrogen or the same or different alkyl radicals. It appears that the presence of the triply bonded nitrilo nitrogen atom has a pronounced influence upon the remainder of the molecule in respect to reaction with halogens, although the reasons for such influence are not at all well understood. Thus, whereas tertiary olefins such as isobutylene normally undergo halogen substitution at ordinary

and reduced temperatures to the substantial exclusion of halogen addition reactions, introduction of the nitrilo group into, for instance, isobutylene to form methacrylonitrile, alters the reactivity so as to substantially obviate halogen substitution under the influence of ordinary or even somewhat elevated temperatures. Thus even at temperatures as high as 200° C. in the case of methacrylonitrile the reaction with chlorine has been found to be without tendency to halogen substitution. The reaction follows instead, in such a case, the course of halogen addition to the methacrylonitrile, forming di-halogen saturated nitriles which differ in essential characteristics from the unsaturated halogen-substituted nitriles obtainable by the process of the present invention. The process of the present invention makes possible for the first time the direct substitutive halogenation of methacrylonitrile and its homologs, and thereby renders production of their halogenation products highly economical and efficient.

The nitriles which may be employed in accordance with the process of the present invention may be either in a highly purified form or they may be in admixture with other materials. The product of reaction obtained in the synthesis of the unsaturated nitriles may be used in the present process without purification if desired. A particularly convenient and economical mode of operation involves, for instance, continuously synthesizing the desired nitrile as by passing vapors of the corresponding unsaturated carboxylic acid and ammonia over alumina or other suitable catalyst at an elevated temperature, and then passing the heated reaction product thereby obtained directly into the present process to form the corresponding halogen substituted unsaturated organic nitrile.

Although the present process is described broadly with reference to the halogen and the halogenation, it is of particular value and utility in respect to chlorination and bromination, via substitution, of the herein defined class of unsaturated organic nitriles. In its preferred embodiment, the process therefore advantageously uses chlorine or bromine as the halogen, and accordingly, results in the preparation of the corresponding chlorinated or brominated unsaturated organic nitriles. The use of chlorine as the halogen is of particular value and its use as the halogen generally is most highly preferred.

In practicing the process of the present invention, the unsaturated organic nitrile and the halogen are brought into reactive contact at an elevated temperature that favors halogen substitution reaction between the nitrile and halogen without substantial degradation of the nitrile reactant and/or product, or possible undesired side reactions, decompositions, etc. The exact range of temperature to be employed in any given instance depends to a certain extent upon the other conditions under which the reaction is effected, such as time of contact, relative proportions of reactants, design of apparatus, etc. The optimum temperature range also differs somewhat with the various nitriles as well as with the different halogens. In each case, however, there has been found to be a minimum temperature favoring substantial halogen substitution of the unsaturated nitrile, and the present process is carried out at a temperature above such minimum temperature. The maximum temperature used in accordance with the process is determined by the maximum temperature to which the re-

actants and/or products can be subjected under the existing conditions without substantial degradation thereof. The process of the present invention is effected at a temperature below this maximum temperature. In general, it may be stated that the minimum temperature desirable is about 250° C., although it will be found that in certain instances either a slightly higher or a slightly lower minimum temperature will be desirable. It generally is not desirable to employ a reaction temperature higher than about 600° C. However, the maximum temperature also is capable of certain variation depending upon purity of products desired, yield desired, existing conditions, etc. In order to obtain optimum results in respect to purity of product, yield, etc. in accordance with the process of the present invention, it is in general preferred to maintain the reaction temperature within the range of from about 350° C. to about 550° C.

The reactants may be introduced into the reaction zone either previously mixed or separately. A particularly convenient procedure involves passing a stream of the unsaturated organic nitrile through an elongated reaction zone such as a suitable reaction tube, in admixture with the selected halogen in the vapor state. The nitrile may be either in the liquid state, if the reaction temperature is below its boiling point at ordinary pressures, or it may be in the vapor state. Because of the possibility that excessive undesired side reactions between the halogen and the unsaturated nitrile such as halogen addition may occur if the reactants are allowed to remain in admixture for any substantial time at a temperature much below the present reaction temperature, it generally is highly desirable to minimize or to entirely eliminate such prior contact at lower temperatures. This may be accomplished, for instance by preheating the unsaturated nitrile to a suitably elevated temperature prior to admixture with the halogen and rapidly introducing into the heated nitrile a stream of gaseous halogen which may be either at normal temperatures or also may have been preheated to an elevated temperature, and then immediately passing the admixed reactants through the reaction zone. It is not always absolutely necessary, however, to resort to preheating of the reactants. In certain cases it is satisfactory to minimize the prior, low temperature contact time as by mixing the two reactants in the cold and then rapidly raising the temperature of the mixture to within the desired temperature range. When there is employed preheating of the reactants, it generally is desirable to preheat to within the temperature range utilized for reaction.

The velocity at which, in the case of continuous operation, the mixed reactants are intermixed and passed through the reaction zone is correlated with the reaction temperature and also is dependent in part upon factors such as design of apparatus, extent of preheating, etc. At any given reaction temperature the reaction mixture is maintained within the reaction zone and at the reaction temperature for a period of time which favors halogen substitution of the nitrile without substantial degradation thereof.

In general, it is desirable with any given apparatus to employ the maximum rate of flow consistent with suitable yields, and hence the minimum time practicable during which the reactants are at the reaction temperature. The halogenation of unsaturated organic nitriles is an exothermic reaction which may under substantially

adiabatic conditions promote flaming or explosion of the reaction mixture. Such possible flaming or explosion may be obviated, for example, by introducing the gaseous halogen into the stream of nitrile at a velocity exceeding that of flame propagation under the existing conditions. Alternatively, the reaction zone may be cooled if desired by suitable means apparent to the art, or a diluent may be included with the reactants to reduce their concentration and hence to minimize danger of flaming or explosion. It also is possible to reduce the volume concentration of the reactants by carrying out the process under reduced pressure, this being particularly suitable in the event it is desired to employ vapor phase reaction with nitriles normally liquid at the reaction temperature but which may be volatilized under suitably reduced pressures. If the design of the apparatus is such that excessive heat loss would occur, thereby cooling the reaction zone to below reaction temperature, external or internal heating means may be provided.

The high temperature substitutive halogenation of unsaturated organic nitriles may in general be effected with either the halogen or the nitrile present in a molar excess. It generally is desired, however, to employ a molar excess of the nitrile over the halogen in the process because of the higher yields based on the halogen that thereby are obtained and because of the greater ease with which the reaction may be controlled. Preferably the reactants are employed in a molar ratio of halogen to nitrile of from about 1:1 to 1:5.

In continuous operation of the present process, the reactants in admixture may be passed through an elongated reaction zone such as may be provided by a suitably heated or cooled tube. The tube may be constructed of any suitable thermally resistant metal alloy, such as iron, ordinary steels, Monel metal, stainless steels, etc., or of other materials such as carbon, quartz, glass, porcelain, etc. The process may be effected with the reactants in either the liquid phase or the vapor phase. Vapor phase reaction frequently is advantageous because of the more complete mixing of the reactants that is possible. However, in the case for example, of halogenation of the higher, less volatile nitriles it frequently is impracticable to employ vapor phase reaction. Effecting the reaction in the liquid phase in such cases therefore is particularly suitable.

The outcome of the process of the present invention is not dependent upon the use or presence of added catalytic materials in the reaction zone, although their presence is not excluded from the broader aspects of the invention. The presence in the reaction zone of an added solid material tends in general to increase the deposition of carbon during the reaction and hence generally is to be avoided. Because of the increased economy and simplicity of operation that result, the process in its preferred embodiments is effected in the absence of any added catalytic material.

In order to avoid the occurrence of undesired continued reaction or secondary or side reactions after the reaction mixture has left the reaction zone, it frequently is desirable to provide means for promptly stopping the reaction. The reaction mixture thus may be cooled and the halogen substituted unsaturated nitrile recovered substantially as soon as the reaction mixture exits from the reaction zone. Separation of the halogen-substituted unsaturated nitrile may be effected, for example, by appropriate use of selective solvents,

by fractional distillation, or by other suitable means. Hydrogen chloride in the reacted mixture may be removed by contacting the mixture with water, which selectively dissolves the hydrogen chloride. Neutralization of the reaction mixture with a suitable base may be employed if desired. Any excess of the initial unsaturated organic nitrile may be recycled through the halogenation process if desired.

The following examples will serve to illustrate certain specific embodiments of the present invention:

Example I

Methacrylonitrile was volatilized and a stream of the vapor was heated to a temperature of about 350° C. A stream of chlorine gas preheated to approximately the same temperature was introduced into the methacrylonitrile vapor in a molar ratio of about 1 mole chlorine to 3.1 moles methacrylonitrile. The stream of mixed reactants immediately thereafter was passed at a rate of .252 total moles reactants per minute through a quartz reaction tube having an inside diameter of 2.0 cm. and a length of 50.4 cm. with a thermocouple 0.4 cm. in diameter extending lengthwise therein. The reactor tube was surrounded by an electric furnace maintained within the temperature range of 580° C. to 595° C. The maximum temperature of the reaction mixture as determined by measurement with the thermocouple was from about 520° C. to 565° C., varying within this range during the course of the experiment.

The reacted mixture was passed directly from the exit of the reactor tube through a cooling means and then contacted with water to separate hydrogen chloride. The organic phase of the binary mixture thus obtained was separated and fractionally distilled.

After removal of unreacted methacrylonitrile the product was found to contain 66 weight per cent alpha-(chloromethyl) acrylonitrile, and 28.5 weight per cent of high boiling material and residue. The product was found to contain less than 8 weight per cent of chlorobutyronitriles (beta-chloroisobutyronitrile and alpha, beta-dichloroisobutyronitrile) and beta-chloro-alpha-methylacrylonitrile. On the basis of chlorine applied (96% reacted) a yield of 2-(chloromethyl) acrylonitrile of 61% was obtained.

Example II

The experiment presented in Example I was repeated, using a reaction temperature of 535° C., a molar ratio of methacrylonitrile to chlorine of 1.9:1, and a flow rate of 0.25 total moles reactants per minute. Only traces of unreacted chlorine were found in the reaction mixture leaving the reaction tube. After fractional distillation and removal of unreacted methacrylonitrile, the product was found to contain 65.5% alpha-(chloromethyl) acrylonitrile produced in a 54% yield based upon the methacrylonitrile consumed.

Example III

Crotononitrile was volatilized and passed in admixture with gaseous chlorine in a molar ratio of crotononitrile to chlorine of 4:1, through the reaction tube used in Example I at about 400° C. Analysis of the product showed that substantially all of the chlorine had reacted. Upon fractional distillation of the reaction product, gamma-chlorocrotononitrile was recovered in good yield.

Example IV

In order to determine the applicability of the present process to the substitutive halogenation of an unsaturated nitrile containing less than four carbon atoms, acrylonitrile was volatilized and passed in admixture with gaseous chlorine, at a molar ratio of acrylonitrile to chlorine of 3.8:1 and a flow rate of 0.06 total mole reactant per minute, through an unpacked quartz tube having an inside diameter of two centimeters and maintained at 520° C. Little reaction was evident. At temperatures of 560-570° C., decomposition was so extensive that carbon deposition plugged the tube in a few minutes.

Example V

Example I was repeated employing bromine in place of the chlorine. Alpha-(bromomethyl) acrylonitrile was produced in good yield.

Example VI

Alpha-beta-dimethylacrylonitrile was volatilized and passed with chlorine, at a molar ratio of nitrile to chlorine of 3.7:1 through a quartz reaction tube maintained within the temperature range of 325 to 487° C. The reaction mixture leaving the reaction tube was cooled rapidly and washed by contacting with dilute aqueous sodium hydroxide. The washed organic phase was fractionally distilled under reduced pressure to provide chlor-alpha,beta-dimethylacrylonitrile in good yield based on the alpha,beta-dimethylacrylonitrile consumed.

In place of the unsaturated organic nitriles utilized in the foregoing examples, there may be employed, for instance, other unsaturated organic nitriles having an olefinic bond in the alpha,beta positions and at least one substitutable hydrogen atom in the allyl position in respect to the olefinic bond. Likewise, there may be employed non-conjugate unsaturated organic nitriles having a substitutable allyl hydrogen atom, as more fully set forth hereinbefore. By means of the process of which the foregoing examples provide certain illustrative embodiments halogen substitution, preferably chlorine or bromine substitution, may be advantageously effected with the consequent formation of valuable and useful products.

We claim as our invention:

1. A process for the preparation of chloro-alpha,beta-dimethyl-acrylonitrile which consists in chlorinating non-catalytically alpha,beta-dimethylacrylonitrile by reacting alpha,beta-dimethylacrylonitrile in the vapor state with gaseous chlorine in the absence of catalysts at a temperature above about 250° C. but below about 600° C.
2. A process for the preparation of gamma-chlorocrotononitrile which consists in chlorinating non-catalytically crotononitrile by reacting crotononitrile in the vapor state with gaseous chlorine in the absence of catalysts at a temperature above about 250° C. but below about 600° C.
3. A continuous non-catalytic process for the preparation of alpha-(chloromethyl)acrylonitrile which comprises mixing a stream of gaseous chlorine with a gaseous stream of methacrylonitrile in a molar ratio of chlorine to methacrylonitrile between about 1:1 and about 1:5, immediately thereafter passing the stream of reactants through a reaction zone maintained at a temperature between about 250° C. and about 600° C. and devoid of substances having catalytic activity

for the reaction, for a period of time which favors chlorine substitution of the methacrylonitrile without substantial degradation thereof, and recovering alpha-(chloromethyl) acrylonitrile from the products issuing from the reaction zone.

4. A process for the preparation of alpha-(chloromethyl) acrylonitrile which consists in chlorinating non-catalytically methacrylonitrile by reacting methacrylonitrile in the vapor state with gaseous chlorine in the absence of catalysts at a temperature above about 250° C. but below about 600° C.

5. A continuous non-catalytic process for the preparation of an alpha,beta-olefinic nitrile substituted in the allyl position relative to the olefinic bond by an atom of a halogen selected from the group consisting of bromine and chlorine which comprises mixing in the vapor phase a halogen selected from the group consisting of bromine and chlorine with an alpha,beta-olefinic nitrile containing at least four carbon atoms and of the general formula

in which one R represents an alkyl group and the second R represents a member of the group consisting of the hydrogen atom and the alkyl groups, said nitrile reactant having an atom of hydrogen in the allyl position relative to the alpha,beta-olefinic bond and containing a total of not over nine carbon atoms, in a molar ratio of halogen to nitrile between about 1:1 and about 1:5, immediately thereafter passing a stream of the mixture through a reaction zone devoid of substances having catalytic activity and maintained at a temperature between about 250° C. and about 600° C., and recovering from the products leaving the reaction zone an alpha,beta-olefinic nitrile substituted in the allyl position relative to the alpha,beta-olefinic bond by an atom of the halogen reactant.

6. A process for the preparation of an alpha,beta-olefinic nitrile substituted in the allyl position relative to the olefinic bond by an atom of chlorine which consists in chlorinating non-catalytically an alpha-alkyl-alpha,beta-olefinic nitrile containing at least four carbon atoms and of the general formula

in which the R directly attached to the alpha carbon atom relative to the nitrillo group represents an alkyl group and the second R represents a member of the group consisting of the hydrogen

5 atom and the alkyl groups, said nitrile reactant having a hydrogen atom directly linked to the saturated carbon atom adjacent to the alpha carbon atom and containing a total of not over nine carbon atoms, by reaction in the vapor phase with gaseous chlorine at a temperature between about 250° C. and about 600° C.

7. A process for the preparation of an alpha,beta-olefinic nitrile substituted in the allyl position relative to the olefinic bond by an atom of a halogen selected from the group consisting of bromine and chlorine, which consists in halogenating non-catalytically an alpha,beta-olefinic nitrile containing at least four carbon atoms and of the general formula

in which one R represents an alkyl group and the second R represents a member of the group consisting of the hydrogen atom and the alkyl groups, said nitrile reactant having an atom of hydrogen in the allyl position relative to the alpha,beta-olefinic bond and containing a total of not over nine carbon atoms, by reaction with a gaseous halogen selected from the group consisting of bromine and chlorine at a temperature between about 250° C. and about 600° C.
